UNITED STATES PATENT OFFICE.

HERBERT SYKES, OF CALGARY, ALBERTA, CANADA, ASSIGNOR OF ONE-HALF TO
J. SERGEANT, OF CALGARY, ALBERTA, CANADA.

PAN-LIFTER.

Specification of Letters Patent. Patented Apr. 18, 1916.

1,179,777.

Application filed June 13, 1915. Serial No. 34,953.

To all whom it may concern:

Be it known that I, HERBERT SYKES, a subject of the King of England, residing at Calgary, in the Province of Alberta and 5 Dominion of Canada, have invented new and useful Improvements in Pan-Lifters, of which the following is a specification.

This invention has for its object the provision of a device designed for lifting and carrying hot plates or like articles, and 10 essentially consists of two relatively movable associated members each formed with a jaw disposed in confronting relation and adapted to engage the sides or upper edges 15 of the article to be lifted.

In carrying out my invention I construct and arrange one of said members for pivotal as well as sliding adjustment whereby the 20 jaw of said member subsequent to being moved approximately into position for engagement with the article to be lifted, may be tilted to obtain an effective purchase upon the same, thereby firmly supporting the article against the danger of dropping 25 the same.

Other objects will appear from the detail description of the invention, the same residing in the specific construction and arrangement of parts hereinafter more fully 30 described.

In the drawing forming part of this application like numerals of reference indicate similar parts in the several views and wherein:-

35 Figure 1 is a view showing the manner of using the device. Fig. 2 is a top plan view. Fig. 3 is a transverse sectional view. Fig. 4 is a side elevation showing the tilted position of one of the members.

40 The device forming the subject matter of my invention essentially consists of two relatively movable members A and B. The member A is constructed from a single wire length of suitable material preferably formed to provide a loop 5 at one end, the 45 terminals 6 of the loop being disposed in contacting engagement and connected together by soldering or any other suitable means. The wire is then extended to provide 50 wide spaced parallel portions 7, having a portion adjacent their free ends converged laterally, the convergently disposed portions 8 being then bent downwardly to provide a depending jaw, the portions 10 of which 55 terminate in offset portions 11. The parallel

portions 7 are connected together at their point of juncture with the convergently disposed portions 8, by means of the strip 12 of any suitable material, preferably steel, having its edges pressed around the parallel 60 portions 7 as shown.

The member B comprises spaced parallel strands of wire 13 formed adjacent their forward ends to provide aligned coils 14 loosely embracing the parallel portions 7 of the member A and providing sliding fulcrums for the member B. The wire forming the coils is then extended outwardly and downwardly as at 15 constituting a jaw disposed in confronting relation with the depending jaw formed on the member A, and coöperating therewith to effectively grip and support the article to be lifted. The opposite ends of each of the strands 13 are bent inwardly toward each other as at 16 75 and thence further extended to provide companion loops 17 which latter surround the parallel portions 7 of the member A. The adjacent portions 18 of the loops are held in contacting engagement with each other 80 by means of the strip 19 as shown.

In use the member A is adapted to be adjusted longitudinally of the member B to accommodate various size articles to be lifted, but in addition to this sliding adjustment, the coils 14 and loops 17 provide for a pivotal movement of the member B, whereby the jaw carried by this member subsequent to being moved approximately 85 into position for engagement with the article to be lifted, may be tilted in the manner shown in Fig. 4 to permit said jaws to obtain an effective purchase upon the article, whereby when said member is lowered and gripped together with the member A constituting a handle for the device, the article is firmly supported between the said members without any danger of dropping the same. Manifestly the device is very efficient 90 for the purpose intended, and by reason of its simplicity of construction together with the fact that it is formed from wire, the device may be manufactured at a comparatively small cost.

It is believed that from the foregoing 105 description the nature and advantages of the invention will be thoroughly understood without requiring a more extended explanation and therefore the same has been 110 omitted.

What is claimed is:—

An article lifter comprising in combination, a member having a loop at one end and spaced parallel portions, the free ends 5 of the latter being divergently disposed and extended downwardly to provide a depending jaw, a plate bridging both said parallel and converging portions and secured thereto to prevent spreading, a second member comprising spaced parallel portions formed adjacent one end to provide aligned coils loosely embracing the parallel portions of the first member and providing sliding fulcrums for said second member, said coils terminating 10 to provide a depending jaw disposed in confronting relation to the first jaw, the opposite ends of the parallel portions of the

second member being extended inwardly and downwardly in contacting engagement and disposed between the parallel portions 20 of the first mentioned member, and thence upwardly at the opposite sides of said parallel portions defining loops whereby said second member is mounted for tilting movement, and a sleeve embracing said contacting portions of said loops to hold the parts operatively associated. 25

In testimony whereof I affix my signature in presence of two witnesses.

HERBERT SYKES.
